UNITED STATES PATENT OFFICE.

HORACE COCHRANE, OF NEWARK, NEW JERSEY.

DESIGN FOR A GAME-BOARD.

SPECIFICATION forming part of Design No. 25,053, dated January 14, 1896.

Application filed September 8, 1894. Serial No. 522,506. Term of patent 3½ years.

To all whom it may concern:

Be it known that I, HORACE COCHRANE, a citizen of the United States, residing at Newark, in the county of Essex and State of New Jersey, have invented and produced a new and useful Design for a Game-Board, of which the following is a specification.

The design has for its object to provide a game-board of novel and ornamental shape and configuration.

The leading features of the design reside in an essentially rectangular-shaped box, the triangular-shaped chambers at the center and U-shaped chambers at the corners, and the peculiarly shaped pockets at the side.

The design is illustrated in the accompanying drawing, in which is shown a perspective view of my newly-invented game-board.

Referring to the drawing, A indicates an oblong box, and at the center of the same is

represented a triangular-shaped chamber B, comprising the narrow vertical walls a, b, and c.

C represent vertical walls at each corner and essentially U-shaped in form, and comprising the curved wall d and straight wall d'.

D represents peculiarly-shaped pockets arranged at each side of the box, comprising a straight wall e and the curved wall e'.

Having thus described my invention, what I desire to secure by Letters Patent is—

The design for a game board substantially as shown and described.

In testimony whereof I affix my signature in presence of two witnesses.

HORACE COCHRANE.
